UNITED STATES PATENT OFFICE.

JOSEPH C. WHITEHOUSE, OF COVINGTON, KENTUCKY.

SETTING FOR PRECIOUS STONES.

1,204,915.

Specification of Letters Patent. Patented Nov. 14, 1916.

Application filed February 1, 1915. Serial No. 5,481.

To all whom it may concern:

Be it known that I, JOSEPH C. WHITEHOUSE, a citizen of the United States, residing at Covington, in the county of Kenton and State of Kentucky, have invented certain new and useful Improvements in Settings for Precious Stones, of which the following is a specification.

It has become the practice in the jewelry industry to set a number of smaller precious stones in a group to resemble the upper portion of the brilliant style of cutting of a single larger precious stone.

It is the object of my invention to provide an improved setting closely resembling a complete brilliant by means which are hereinafter more particularly described and claimed.

In the drawings: Figure 1 is a side elevation of my improved setting. Fig. 2 is a plan view of the same. Fig. 3 is a bottom view of the same. Fig. 4 is an axial section of the same taken on the line 4—4 of Fig. 3. Fig. 5 is a plan view of the cluster-plate. Fig. 6 is a side elevation of the same. Fig. 7 is a side elevation showing my improved device secured in a larger setting which may be part of a scarf-pin, ring or other piece of jewelry. Fig. 8 is a vertical axial section taken on the line 8—8 of Fig. 7; and Fig. 9 is a similar view of a modification of my improved setting.

A cluster-plate 11 is arranged to receive a group of precious stones 12. It is shown provided with bores 13, shown tapering toward their lower ends, in which the stones 12 are fastened as by bending the edges of the upper ends of the walls of the bores over the edges of the stones. The plate is preferably provided with a flat central portion 14 from which the plate slants downwardly, as shown at 15, toward the peripheral edge of the cluster-plate. The central portion is provided with one of the bores 13 which is in line with the axis of the setting, the downwardly slanting portion being provided with bores surrounding the top portion, so that when the small stones are set in the bores, the setting may resemble the crown portion of a single brilliant cutting of precious stone, the central portion resembling the table and the peripheral edge 16 of the cluster-plate resembling the girdle of the brilliant.

17 is a body of light-transmitting sub-

stance, less precious than the diamonds, or other precious stones, exemplified at 12, and may for instance be crystal, glass, white sapphire, or other suitable light-transmitting substance, that is to say, said lower body 17 has light properties for transmitting light therethrough similar to the light properties of the smaller precious stones 12 set in the cluster-plate, whether these smaller precious stones be diamonds, rubies, sapphires, emeralds, or other precious stones. The body 17 is preferably provided with facets to resemble the pavilion portion of a brilliant cutting of precious stone, and is exemplified as having under skew facets 18 and lower facets 19 formed thereon. It is fastened so as to form the under portion of my improved setting. Thus the cluster-plate is provided with an annular periperal downwardly extending flange 20 within which the upper peripheral edge of the body 17 is received, the flange being arranged to be bent inwardly for securing the body 17 in place. If desired, the cluster-plate may be provided with claws 21 which extend downwardly, the body 17 being arranged to be received between the claws, and the claws bent under the upper end of the body 17 for clamping the body to the under side of the cluster-plate. The flange and claws may 70 be selectively or collectively employed. The upper portion of the body 17 of light-transmitting substance may be provided with a recess 22, in which the lower ends of any of the small stones 12 which project below 75 the lower ends of the bores 13 are received. If desired, the recess 22' in the body 17' (see Fig. 9), may be so formed that its inner wall will conform substantially to the general taper of the outer periphery of the body 80 17 of light-transmitting substance. The inner wall may be provided with a coating 23 of light-reflecting substance, such as foil or mercury, in order to reflect the light through the facets for refracting the same, 85 the body of light-transmitting substance being at the outside of this coating.

My improved setting may be employed as a single stone of brilliant cutting and be set in a larger setting 24, which may be 90 part of a scarf-pin, ring, or other piece of jewelry. When so set the prongs 25 of the larger setting 24 are arranged to cover the claws 21 on the cluster-plate so as to hide the same, the prongs 25 being bent as claws 100 110

across the girdle of the cluster-plate between the small stones 12.

Having thus fully described my invention, what I claim as new and desire to secure by 5 Letters Patent, is:

1. A setting of the character described, comprising a cluster-plate and a group of small stones, said cluster-plate provided with upwardly extending fastening means 10 for receiving said group of small stones to resemble the crown portion of a precious stone and with downwardly opening clamping means, and a lower body portion having light properties similar to the light properties 15 of said small stones and provided with facets to resemble the lower portion of said precious stone, said clamping means rigid with said cluster-plate and bent under the upper edge of said lower body portion.
2. A setting for precious stones to resemble a brilliant cutting of a single stone comprising a cluster-plate provided with setting recesses for a group of small precious stones, small precious stones secured in said 25 recesses to resemble the crown of the brilliant cutting, and a lower less precious body provided with facets which forms the pavilion portion of the brilliant cutting, said lower less precious body having light properties similar to the light properties of said 30 small precious stones, said cluster-plate provided with downwardly extending clamping means clampingly received about the upper edge of said lower less precious body.
3. A setting for small stones to resemble a single stone comprising a cluster-plate provided with setting bores for a group of small stones, said bores opening upwardly for receiving said stones and opening downwardly 40 for permitting the lower ends of said stones to project therethrough, small stones secured in said bores, and a lower body having light properties similar to the light properties of said small stones and provided with facets to resemble the lower portion of said single 45 stone, said cluster-plate provided with downwardly extending clamping means clampingly received about the upper edge of said lower body for clamping said lower body to said cluster-plate, and said lower body provided with an inner depression extending downwardly thereinto from its top 50 in which the lower ends of said small stones

of said group of small stones projecting through said bores are received. 55

4. A setting to resemble a brilliant cutting comprising a cluster-plate provided with setting recesses for a group of small precious stones, small precious stones secured in said recesses to resemble the crown portion of the brilliant cutting, and a lower less precious body having light properties similar to the light properties of said small precious stones and provided with facets to resemble the pavilion portion of the brilliant cutting, the upper end of said last-named part being of a diameter substantially the same as the diameter of said group of small precious stones, said cluster-plate provided with downwardly extending clamping means clampingly received about the upper edge of said lower less precious body, and said lower less precious body provided with an inner cavity the inner wall whereof is provided with a light reflecting 75 substance.

5. In combination, a setting of the character described comprising a cluster-plate provided with setting bores for a group of small stones, said setting bores opening upwardly for receiving said stones, and small stones secured in said bores to resemble the crown portion of a precious stone, a lower body having light properties similar to the light properties of said small stones and of substantially the diameter of said cluster-plate and provided with facets to resemble the lower portion of said precious stone, the peripheral edge of said cluster-plate provided with downwardly extending claws 90 clampingly received about the upper edge of said lower body for clamping said lower body to said cluster-plate, and an inclosing setting comprising upwardly extending setting-prongs in line with and received over 95 said claws, the upper ends of said setting-prongs being clamped over said peripheral edge of said cluster-plate.

In testimony whereof, I have hereunto signed my name in the presence of two subscribing witnesses.

JOSEPH C. WHITEHOUSE.
